IRONING MACHINE

William J. Asher, Colorado Springs, Colo., assignor to The Prosperity Company, Inc., Syracuse, N. Y., a corporation of New York

Application February 23, 1938, Serial No. 192,155

3 Claims. (CL 38—9)

The present invention relates to power driven ironing machines and particularly to machines of this class in which the ironing operations are carried out upon steam heated drums or cylinders.

In my Patent No. 1,809,467, granted June 9, 1931, there is disclosed a power operated ironing machine of this class particularly suitable for use in the ironing of sheets, blankets, handkerchiefs and all types of garments, regardless of sizes, shapes and thicknesses, and with or without buttons, the patented machine embodying two heated cylinders mounted for rotation about parallel axes and two endless aprons by means of which the articles to be ironed are first pressed against the cylindrical surface of the first cylinder, then transferred to the second cylinder for a second pressing or ironing operation and finally discharged, various accessory mechanisms being employed in conjunction with the aprons and drums to facilitate the handling of the articles. While the machine disclosed and claimed in the aforementioned patent has been found to be eminently suitable for accomplishing its intended purposes, I have discovered, as a result of further experimentation, that by making certain changes in and to the various mechanisms incorporated therein, by rearranging certain of its elements, and by incorporating certain additional parts of novel design, an improved machine of increased efficiency in operation can be produced while at the same time the cost of manufacture is decreased.

The invention embodies several novel features of considerable practical importance including an improved mechanism for controlling the movements of the several padded rollers a group of which are associated with each of the ironing cylinders. Such mechanism comprises a tension spring connecting at all times a central adjusting member and a roll carrying rocker, in combination with a thrust rod housed within the spring and designed to transmit the thrust of the adjusting member to the rocker.

A further feature of the improved machine comprises the combination, with an ironing cylinder and apron, of an improved pressure roller mounting adjacent the point where the apron reverses the direction of its movement. The pressure roller is directly mounted on a sub frame rockably mounted on the main frame and normally overlies the doffing bar, the bar being rendered accessible after the sub frame and certain associated tapes are rocked upwardly.

It will be appreciated by one skilled in the art

that minor changes in the design and arrangement of the component elements of the invention may be readily made without losing the advantages thereof.

5 A feature of the present machine is a device or mechanism for effecting dislodgment of articles from the first apron at the point where this apron is supposed to discharge such articles onto the second apron, the means provided effecting 10 dislodgment of such articles despite the tendency of such articles to cling to the aprons.

In the accompanying drawings:

Figure 1 is a side view of the entire machine;
Figure 2 is a rather diagrammatic view which 15 corresponds approximately to a longitudinal vertical section through the machine taken inside of a side frame, showing the arrangement of cylinders, aprons, tapes, pressure rollers and tape and apron guide rollers;

20 Figure 3 is a partial longitudinal section through the machine at one end thereof, showing the article feeding mechanism in detail;

Figure 4 is a section on line 4—4 of Figure 3;
Figure 5 is a section on line 5—5 of Figure 3;
Figure 6 is a section on line 6—6 of Figure 5;
Figure 7 is a section on line 7—7 of Figure 3;
Figure 8 is a side elevation of portion of a doffing bar showing attached doffing blades;

25 Figure 9 is a view, partially in side elevation, and partially in section, of one of the pressure rollers and its adjusting means;

Figure 10 is a perspective view of a portion of one end of the machine, showing details of the feed mechanism;

30 Figure 11 is a side view of a portion of the mechanism illustrated in Figure 10.

It will be understood that all of the operating parts of the machine are mounted in a suitable frame of such size and weight that these parts 40 are adequately supported, the frames being of such character, however, that the machine as an entirety occupies a minimum of floor space. One of the side members of the frame is indicated at 10 in the drawings there being two of these 45 side frame members, substantially identical, and which preferably rest upon a flat base 11, being integral with or rigidly secured to such base. For the purpose of convenience in manufacture both base and side frame members may be formed in two or more parts if desired.

The ironing cylinders are indicated at 12 and 13, respectively, cylinder 12 being hereinafter designated the first cylinder inasmuch as the articles to be ironed are first fed to this cylinder and cylinder 13 being hereinafter designated

the second cylinder. Each cylinder is hollow and means is provided for introducing live steam into the interior thereof so that its cylindrical outer surface may be heated to the temperature desired for ironing purposes. Each cylinder is likewise provided with aligned axially projecting trunnions at its ends and by means of which it is rotatably supported in bearings mounted upon the side members of the frame, two trunnions being indicated at 14 and 15 in Figure 2 and bearings at 16 and 17 in Figure 1. Associated with the first cylinder are seven pressure rollers which are indicated at 18, 19, 20, 21, 22, 23 and 24 respectively and associated with the second cylinder are six pressure rollers which are indicated at 25, 26, 27, 28, 29 and 30 respectively.

The two endless aprons are indicated at 31 and 32, respectively, these aprons being guided in closed endless paths by the cylinders 12 and 13, the pressure rollers, and by apron guide rollers. Thus guide rollers 34, 34', 35, 36 and 37 are associated with the first apron, guide rollers 38, 39, 40, 41 and 42 with the second apron, and a guide roller 43 serves as a common guide roller for both aprons at one point. Also associated with the first apron is a combination tensioning and guide roller 44 and with the second apron a combination tensioning and guide roller 45. The directions of movement of the two aprons along the endless paths which they follow are indicated by arrows in Figure 2 and it will be perceived that the aprons are brought together at a point adjacent pressure roller 23, passed downwardly intermediate the cylinders 12 and 13 in close proximity to each other so as to maintain therebetween, and without slippage, an article or garment, and continue to move together until after passage over guide roller 43, where they again diverge, pressure rollers 22, 25, 26, and 27 serving to guide the aprons while they are moving in close relationship along parallel paths. A series of feed tapes are indicated at 46, a plurality of endless feeding cords at 47 and a series of parallel article guiding tapes at 48, a final series of endless tapes being indicated at 49 adjacent the discharge end of the machine. Doffing mechanisms are indicated generally at 50 and 51. From an inspection of Figure 2, in which figure the directions of rotation of the cylinders are indicated by arrows, and the directions of movement of the aprons and tapes are also indicated by arrows, the path of movement of an article through the ironing machine may be generally understood and will now be described.

Thus the article is first placed upon the upper reach of the feeding tapes 46, being passed inwardly toward the surface of the first cylinder 12 by these tapes so that its leading edge is projected into close proximity to the surface of the cylinder, turning downwardly so as to be gripped between the apron 31 and the cylinder surface. After the leading edge of the article is thus gripped the remainder is drawn after it into contact with the surface of the cylinder automatically by the movement of the cylinder and because of the coaction therewith of apron 31, and passes around the cylinder until it is removed or stripped therefrom by the doffing mechanism 50. It is then connected around the pressure roller 24 with the aid of the tapes 48 and moves upwardly, still resting upon the apron 31, until it passes over pressure roller 23 and starts downwardly between the cylinders. At this point it is engaged on its upper surface by the second apron 32 and is tightly held between the two

aprons moving along parallel paths until it passes around and over the guide roller 43. At this point the aprons diverge, the second apron, carrying the article, moving downwardly and around the pressure roller 27, into contact with the cylinder 13, then around the cylinder to the pressure roller 28, thence upwardly to and over guide roller 42 from which point it moves again to guide roller 38. The article of course is ironed a second time while passing around cylinder 13 and is removed from the surface of the second cylinder by doffing mechanism 51, passing onto the delivery tapes 49 and thence upwardly and outwardly to the point of discharge indicated at D. The operation of the machine is continuous and articles may be fed thereto in rapid succession. Advantageously the second cylinder, and the second apron, are driven at speeds very slightly greater than the speed at which the first cylinder and apron are driven. During their travel over the surfaces of the heated cylinders the moisture of each garment is completely driven off and when the garment or article reaches the final point of discharge D it is completely ironed and ready to be folded and packaged for delivery.

Each pressure roller illustrated is of the padded type and provided with axial trunnions at its ends, each such trunnion being housed within a bearing 55 integral with a rocker 56. Each rocker 56 is pivoted at 57 to the frame of the machine and the rockers are so disposed with reference to the axes of the cylinders that their free ends may be oscillated toward and away from the adjacent cylinder axis so that, by simultaneously rocking the pair of rockers which support the trunnions of any particular pressure roller such roller may be moved toward or away from the axis of the associated cylinder or, in other words, moved from operative to inoperative position as desired.

Mechanism is provided for simultaneously moving from operative to inoperative position, or vice versa, all pressure rollers of the entire machine and this mechanism will now be described. Mounted upon each trunnion 14 of the first cylinder 12 is a ring 58, ring 58 being freely rotatable on the trunnion and being normally stationary. The free ends of the several rockers 56 associated with the pressure rollers are connected to the rings 58 so that, when rings 58 are rotated, rockers 56 will be simultaneously actuated. All of the rockers 56 associated with the second cylinder 13 are connected to the rings 58 also associated with said cylinder by means of spring devices such as indicated in Figure 9. Pressure rollers 19, 20, 21 and 22 associated with the first cylinder are likewise connected to the corresponding rings. The connecting means disclosed in Figure 9 comprises essentially a tension spring 60 of helical type within the end windings or convolutions of which are threaded the externally threaded blocks 61 and 62, the spring ends being thus permanently connected to these blocks. Integral with block 61 is a rod-like extension 63 the free end of which is connected by means of a pivot 64 with the rotatable ring 58. Block 62 is connected to the free end of the associated rocker 56 by means of an eye bolt 65 one end of which is pivotally connected to the block as shown and the shank of which extends through an aperture formed in rocker 56, the shank of the bolt being threaded and having thereon securing nuts 67 which maintain a definite relationship between the bolt and rocker while at the same time permitting an adjustment

of the bolt to be made to increase or decrease the tension in spring 60. Within the spring 60 is a tube 68 which may be rigidly connected to either block 61 or 62 or simply freely retained within the spring, as indicated in Figure 9. During operation of the machine the rings 58 are so adjusted that tension is applied to all of springs 60, thus holding the pressure rollers to which these springs are connected through the rockers shown in tight engagement with the aprons encircling the cylinders with which the pressure rollers are associated. The degree of tension may be varied by adjusting the position of rings 58, as will be clear, and the rollers caused to bear more or less heavily upon the apron, as may be desired. When the machine is stopped or shut down the control rings 58 may be rotated in such manner as to first relieve the tension in springs 60 and thereafter further rotated to cause the blocks 61 to strike the adjacent ends of thrust rods or tubes 66, forcing these rods into engagement with blocks 62 and thus positively thrusting the free ends of rockers 56 away from the cylinders, these rockers carrying bearings 55 and the pressure rollers with them. Pressure of the rollers upon the apron may be relieved in this manner so that the aprons are not tightly engaged with the heated cylinders while the cylinders are not in rotation and hence will not be scorched.

As previously explained, the doffing devices 50 and 51 underlie the pressure rollers 24 and 28 respectively and I therefore mount these pressure rollers in such manner that they may not only be moved radially of the respective cylinders with which they are associated, in the manner and by the means above described, but also in such manner that they may be bodily displaced upwardly with reference to the doffing devices in order that access may be had to these devices for inspection and repair. Thus the rockers 56 which carry the bearings in which the trunnions or pressure rollers 24 and 28 are rotatably supported are not pivotally connected directly to the main frame, as are the rockers upon which the other pressure rollers are mounted, but are pivotally connected to sub-frame structures which structures are in turn pivotally supported in the main frame. For a clear understanding of the manner in which the pressure roller 24 is supported reference may be had to Figures 10 and 11 of the drawings. The sub-frame upon which pressure roller 24 is mounted by means of its rockers 56 comprises the bracket-like side members 75, each pivotally connected to the adjacent side of the main frame by a pivot, one of which is indicated at 76, the two members 75 being rigidly interconnected by means of a tape guide bar 77. Each sub-frame side member 75 has formed therein a plurality of apertures 78, disposed along an arc of a circle centered on the axis of pivot pin 76. The adjacent main frame member is provided with an aperture 79 with which any one of the apertures 78 may be brought into register by swinging the sub-frame about its pivotal axis and, by inserting a pin 80 into aligned apertures 78 and 79 the members 75 may be positively locked in any one of several positions. At its lower end each side portion 75 of the sub-frame is provided with a thickened portion or boss 81 having an aperture 82 therein for the reception of the end of a tilting lever, shown in dotted lines at 83 in Figure 16, and by means of which an operator can apply to the sub-frame sufficient force to tilt it to the desired extent about its pivotal axis. Lever 83 is freely

insertable or removable and is inserted into the aperture 82 only when the pressure roller 24 is to be lifted. By its use the sub-frame may be lowered into the position in which it is shown in full lines in Figure 11, or may be rocked in a clockwise direction until it occupies the position in which it is shown in dotted lines in this figure. The sub-frame is normally retained in its lowermost position by means of a locking bolt 85 one end of which is pivotally connected to the main frame and the other end of which passes through an aperture provided in a laterally projecting lug 86 integral with the sub-frame, the pins 80 not ordinarily being employed to maintain the sub-frame in its operative position. A nut 87 on the threaded bolt 85 prevents clockwise movement of the sub-frame. An adjusting screw 88 has threaded engagement with a second aperture formed in lug 86 and disposed parallel to the aperture which receives bolt 85, the lower end of this adjusting screw 88 bearing upon the main frame and its upper end having thereon a lock nut 89. By the conjoint action of the securing bolt 85 and adjusting screw 88 the sub-frame can be maintained rigidly in a desired position of permanent angular adjustment with respect to the main frame. Naturally prior to tilting of the sub-frame to elevate the pressure roller 24 the nut 87 is released. With the sub-frame in its dotted line position, and pressure roller 24 raised, ready access may be had to the doffing device 50.

A tape guiding roller is indicated at 90 and it will be perceived that the roller extensions or trunnions 90' are mounted in bearings 91, fixed on the ends of rocking arms 92, pivotally mounted upon pins 93, fixed in bushings 94 rigid with the sub-frame side 75 at their upper extremities. Roller 90 may therefore be swung upwardly about the aligned axes of pins 93 and such movement will occur when the sub-frame is rocked and pressure roller 24 elevated, roller 90 moving from the position in which it is shown in full lines in Figure 11 to the position in which it is shown in dotted lines in this figure. Roller 90 comprises a guide roller for the series of spaced parallel tapes 48 which tapes also are guided so as to move along closed endless paths between pressure roller 24, between doffing bar 98, and between upper guide rod or roller 99. The doffing bar 98 is circular in cross-section and its ends 100 are fixed in the side members of the main frame. Upon the bar are mounted the individual doffing blades 101 each blade having an elongated horizontally disposed portion 101' with an edge 101² adapted to rest against the smooth cylindrical surface of cylinder 12 and having a reduced portion or shank 101³ which is curved to encircle rod 98 and the end of which is secured by screws 102 to the doffing bar. The doffing blades are fabricated of spring steel and are quite flexible. The initial tension of the blades is such that their upper edges 101² are always lightly pressed against the cylindrical surface of the cylinder 12 so as to intercept and peel off from this cylinder articles which tend to cling to the same and to direct these articles onto the tapes 48, by means of which, in conjunction with the apron 31, they are carried around the pressure roller 24. It will be observed from an inspection of Figure 8 that tapes 48 pass between the shanks 101³ of the doffing blades 101 so that these portions of the doffing blades likewise comprise lateral guides for the tapes 48.

Whenever it is necessary that access be had to

the doffing blades the sub-frame carrying rockers 56 upon which roller 24 is mounted is raised to its dotted line position (Figure 11), thus providing ample clearance. It will be observed that there is secured to the upper face of the tape guiding bar 11, which upper face is flat, one margin of an upwardly concave plate 106 which extends toward the doffing bar. The plate 106 intercepts any downhanging portions of the garments or other articles passing around pressure roller 24, and which may fall downwardly between the tapes 46, and prevents these smaller article portions, such for instance as apron strings and the like, from becoming entangled in the article feeding mechanism located just below this pressure roller.

The article feeding mechanism includes the series of parallel endless tapes 46 previously mentioned, these tapes passing around the tape driving roller 107 and around the substantially horizontally arranged feed table 108. The ends of roller 107 are mounted in bearings 109 which bearings in turn are supported upon the ends of rods 110 slidably mounted in apertures formed in brackets 111, each bracket being provided with a set screw 112 for frictionally retaining the associated rod 110 in any position to which it may be adjusted. In this manner the axis of the tape driving roller 107 may be adjusted with respect to the feed table 108 and the tapes 46 placed under the desired tension. Each bracket 111 is pivotally mounted upon a pin 113 extending laterally from the adjacent side member of the main frame so that it may swing angularly in a vertical plane. Each bracket is provided with a lateral extension 111' having an adjusting screw 114 passing through its outer end, the lower end of which screw rests upon the upper surface of the adjacent portion of the main frame, the screw being likewise provided with a lock nut 115. By rotating the screws 114 the brackets 111 may be elevated or depressed as desired and the angularity of the feed table modified within limits. Connecting brackets 111 is an angle bar 116, this angle bar immediately underlying the feed table 108.

As may be perceived from Figure 7 the ends of the feed table 108 are secured to the angle bar by means of screw bolts, one of which is indicated at 117, spacers 118 interposed between the ends of the feed table and the angle bar spacing these members apart as shown clearly in the drawings. Intermediate its ends the feed plate is supported from the angle bar upon the reduced upper ends of a plurality of screws 119 which have threaded engagement with interiorly threaded apertures formed in the angle bar and each of which is likewise provided with a lock nut 120. By loosening the lock nuts 120 the screws may be vertically adjusted and a longitudinal curvature (transversely of the machine) may be imparted to the feed table. The adjusting screws likewise comprise tape guiding members, their upper ends being rounded and smooth and a tape 46 passing between each pair of adjacent screws. In practice the screws 119 are so adjusted that the feed table is longitudinally curved or arched upwardly from its ends to its midpoint for a purpose to be hereinafter set forth. Roller 107 has a sprocket and chain connection to a driving mechanism, for instance being driven from the cylinder 12 by means of sprocket 121, chain 122 and sprocket 123.

The forward longitudinal edge of the feed table 108 is rounded and comprises a guide surface around which the tapes move in order to effect

reversal of direction of movement. A feed roller is indicated at 125, this roller being thickly padded but being relatively light in weight, the ends of the roller being mounted in bearings carried by 5 tilting levers, one of which is indicated at 126 and is shown to be pivoted at 127 upon a standard 128 (Fig. 3) mounted upon the end of the feed table. At its opposite end lever 126 is provided with a set screw 130 the lower end of which is adapted to 10 strike the plunger 131 of a switch 132. This switch is included in the circuit for the driving motor 133 and opens the circuit when the plunger 131 is actuated by the lever 126.

Disposed transversely of the machine is a serpentine guide wire 134, this wire being positioned in close proximity to the surface of the first cylinder 12 and comprising a guide means for the plurality of parallel cords 47 which extend around the feed roller 125 and are driven by frictional engagement with said roller. It is the function of the cords 47 to prevent upward deflection of the leading edge of any article fed to the machine, due to possible adherence of such article to the surface of roller 125, and to ensure that this edge first contacts with the cylinder 12 when moving downwardly, thus preventing folding and wrinkling of the forward margin of any article fed to the machine.

In the normal operation of the feeding mechanism the leading edge of an article to be ironed, such for instance as a sheet, is laid smoothly over the tapes 46 and is moved forwardly with these positively driven tapes, eventually passing under feed roller 125, thence into contact with cylinder 12, and is immediately thereafter gripped between the cylinder and the associated apron. The padded roller 24 is cylindrical whereas the feed table underlying the same is longitudinally arched i. e., is arched transversely of the machine so that 30 the midportion of the roller bears more heavily upon the table than do its ends. As the feed roller 125 is not positively driven, but on the other hand is merely frictionally driven by the work, it will be perceived that it opposes the forward movement of the central portion of a piece of work into the machine to a greater extent than it opposes the lateral portions of such piece, or, in other words, exerts a greater frictional retarding force 35 against the central portion of an article being fed 40 than against its lateral portions. As a result of this central retardation of the work the edges of wide pieces go forward more freely and the work as it comes from the machine will be much more likely to have its original shape. It has been 45 found that this facilitates ironing without wrinkling especially where, due to previous washing and extracting operations, the edges of the sheet have been stretched to a greater extent than the body thereof. Should it happen that a piece of 50 work be delivered to the feed table in folded condition so that several thicknesses of the work pass under the roller 125 simultaneously this roller will be elevated to such an extent that the set screw 130 will depress the plunger 131 of switch 55 132 and thus open the circuit which includes the driving motor 133, causing the machine to stop. The roller 125 therefore comprises a portion of a safety device as well as performing its above specified functions as a feed roller and as a guide for the cords 47.

It has previously been stated that the doffing device 51 underlies a pressure roller 28 mounted so that it may be bodily elevated when necessary to give access to the doffing device. The rockers 56 which carry pressure roller 28 are therefore not

directly pivoted to the main frame but are on the other hand pivoted to members 138 which are in turn pivotally connected to the main frame, the point of pivotal connection of one of these members to the frame being indicated at 139. Each member 138 is provided with a screw bolt 140 by means of which it is tied to a lug 141 comprising a portion of the main frame and is likewise provided with an adjusting thrust screw 142, member 138 being rigidly held in any position of adjustment to which it may be moved by the coaction of the securing and adjusting bolts just described. Members 138 may likewise be provided with apertures for the reception of lifting levers, as in the case of the sub-frame at the opposite end of the machine previously described so that the pressure roller may be manually elevated by means of such levers and held in elevated position while adjustment of the doffing mechanism is being effected.

It has been previously explained that the first and second aprons travel in parallelism from the combination pressure and guide roller 23 to a point just beyond the guide roller 43, frictionally holding between them the pieces of work which have already been ironed upon the first cylinder and which are next to be subjected to the ironing action of the second cylinder. After passing around the guide roller 43 the two aprons move along divergent paths, as clearly shown in Figure 2. As there is some tendency for the work to continue to adhere to the first apron instead of falling upon the second apron as intended, so as to be carried around the second cylinder, means is provided for vibrating that reach of the first apron which lies intermediate the guide rollers 43 and 37. Likewise means is provided for vibrating that reach of the second apron which lies between the combination guide and pressure roller 28 and guide roller 42 in order that any articles which may tend to cling thereto shall be shaken loose so as to fall upon the delivery tapes 49.

In operation the cylinders 12 and 13 are driven from motor 133 by means of the gearing shown, including main gears 170 and 171, and pinions 172 and 173 rigid with these gears, the pinions meshing with teeth formed on or secured to the cylinders respectively. Main gear 170 is connected to motor 133 by pinion 175, sprocket 176,

and chain 177. By means of a chain 178 and sprocket 179 roller 39 is driven from main gear 171 and thus a driving force imparted to the second apron. The first apron is driven only because of its contact with the first cylinder and second apron. All of the pressure rollers are driven frictionally only.

Having thus described the invention, what is now claimed as new and desired to be secured by Letters Patent is:

- 5 1. In an ironing machine, in combination, an ironing cylinder mounted for rotation about a fixed axis, an endless apron associated therewith, a roller disposed parallel to the cylinder axis and around which the apron passes after leaving the cylinder to reverse its direction of movement, doffing means below the roller, a series of endless tapes for cooperating with the apron in passing articles removed from the cylinder by the doffing means, around the roller and upwardly, guide means for said tapes including a member disposed parallel to the cylinder axis and disposed between the inner and outer reaches of said tapes, and a shield mounted on said member, for the purpose set forth.
- 10 2. In an ironing machine, in combination, an ironing cylinder, a padded pressure roller, a rocker upon which the pressure roller is mounted, and means for controlling the action of the roller comprising a tension spring anchored at one end to a movable member positioned adjacent the cylinder axis and at its other end to said rocker, and a thrust rod housed within the spring but not operatively connected thereto, for transmitting the thrust of said member to said rocker.
- 15 3. An ironing machine of the class described comprising in combination, a main frame, a cylinder rotatably mounted in the frame, a doffing bar fixed in the frame, a sub-frame rockably mounted on the main frame, a padded pressure roller carried by the sub-frame, means for moving the pressure roller toward or away from the cylinder, and a tape guide rockably mounted on the sub-frame, the pressure roller normally closely overlying the doffing bar and the bar being accessible only after the tape guide and sub-frame are rocked upwardly.
- 20 4. In an ironing machine, in combination, an ironing cylinder, a padded pressure roller, a rocker upon which the pressure roller is mounted, and means for controlling the action of the roller comprising a tension spring anchored at one end to a movable member positioned adjacent the cylinder axis and at its other end to said rocker, and a thrust rod housed within the spring but not operatively connected thereto, for transmitting the thrust of said member to said rocker.
- 25 5. An ironing machine of the class described comprising in combination, a main frame, a cylinder rotatably mounted in the frame, a doffing bar fixed in the frame, a sub-frame rockably mounted on the main frame, a padded pressure roller carried by the sub-frame, means for moving the pressure roller toward or away from the cylinder, and a tape guide rockably mounted on the sub-frame, the pressure roller normally closely overlying the doffing bar and the bar being accessible only after the tape guide and sub-frame are rocked upwardly.
- 30 6. An ironing machine of the class described comprising in combination, a main frame, a cylinder rotatably mounted in the frame, a doffing bar fixed in the frame, a sub-frame rockably mounted on the main frame, a padded pressure roller carried by the sub-frame, means for moving the pressure roller toward or away from the cylinder, and a tape guide rockably mounted on the sub-frame, the pressure roller normally closely overlying the doffing bar and the bar being accessible only after the tape guide and sub-frame are rocked upwardly.
- 35 7. An ironing machine of the class described comprising in combination, a main frame, a cylinder rotatably mounted in the frame, a doffing bar fixed in the frame, a sub-frame rockably mounted on the main frame, a padded pressure roller carried by the sub-frame, means for moving the pressure roller toward or away from the cylinder, and a tape guide rockably mounted on the sub-frame, the pressure roller normally closely overlying the doffing bar and the bar being accessible only after the tape guide and sub-frame are rocked upwardly.
- 40 8. An ironing machine of the class described comprising in combination, a main frame, a cylinder rotatably mounted in the frame, a doffing bar fixed in the frame, a sub-frame rockably mounted on the main frame, a padded pressure roller carried by the sub-frame, means for moving the pressure roller toward or away from the cylinder, and a tape guide rockably mounted on the sub-frame, the pressure roller normally closely overlying the doffing bar and the bar being accessible only after the tape guide and sub-frame are rocked upwardly.
- 45 9. An ironing machine of the class described comprising in combination, a main frame, a cylinder rotatably mounted in the frame, a doffing bar fixed in the frame, a sub-frame rockably mounted on the main frame, a padded pressure roller carried by the sub-frame, means for moving the pressure roller toward or away from the cylinder, and a tape guide rockably mounted on the sub-frame, the pressure roller normally closely overlying the doffing bar and the bar being accessible only after the tape guide and sub-frame are rocked upwardly.

WILLIAM J. ASHER.
